PANEL CARRIER

Ralph N. Geffroy, South Bend, Ind., assignor to
 Mastic Asphalt Corporation, South Bend, Ind.,
 a corporation of Indiana

Application March 8, 1939, Serial No. 260,556

12 Claims. (Cl. 198—180)

This invention relates to panel carriers, and particularly to a carrier for a panel of insulation board or the like and employed in an apparatus for treating or processing such panel, such as that disclosed in the co-pending application of Gilbert J. Snyder, Ser. No. 260,554, filed March 8, 1939.

In rapid handling of large numbers of insulation boards in quantity production for dipping to substantially uniformly coat the same, and for preheating and drying the same, as in apparatus of the type shown in the said Snyder application, various requirements as to the panel carrier exist. Thus, the carriers must (a) be adapted for automatic manipulation to grip and to release the boards or panels; (b) they must be adapted to hold a large number of panels in spaced juxtaposed position; (c) they must have operating or control parts located to be clear of the material into which the panels are dipped; (d) they must grip the panels to expose all surfaces thereof for coating; and (e) they must be maneuverable to accommodate movement of the panels in an undulating path without altering points of contact with the panel.

Therefore, it is the primary object of this invention to provide a simple carrier construction meeting the above requirements.

A further object is to provide a carrier having a normal spring pressed position in reference to a support and shiftable from said normal position against the action of said spring.

A further object is to provide a carrier comprising a head carrying juxtaposed fixed and rotatable members having gripping members at their lower ends, and means adjacent said head for rotating the rotatable members and their gripping members.

A further object is to provide a carrier having depending gripping elements engaging restricted points of a panel, and means for preventing said panels from tilting.

Other objects will be apparent from the description and appended claims.

In the drawing:

Fig. 1 is a top plan view of the carrier.

Fig. 2 is a side elevation of the carrier.

Fig. 3 is an enlarged detail sectional view taken on line 3—3 of Fig. 2.

Fig. 4 is a fragmentary enlarged view, with parts shown in section, illustrating the gripping elements of the rotatable members of the carrier.

Fig. 5 is a fragmentary enlarged view, with parts shown in section, illustrating the gripping

elements of the stationary members of the carrier.

Referring to the drawing which illustrates the preferred embodiment of the invention, the numeral 1 designates a conventional roller chain constituting a conveyor and adapted to roll on and be positioned by a guide such as angle iron 2. Two chains in parallel spaced relation are employed, each having an independent guide, and said guides being of complementary form whereby corresponding points on each chain and guide are transversely aligned and of equal elevation.

The carriers 9 extend transversely between 15 and are secured to conveyor chains 1. Each of the chains 1 has a plurality of ears 10 projecting at the inner side thereof in spaced relation, with ears on the respective chains transversely aligned. Upon ears 10 rest the reduced ends 11 of a rigid 20 transverse bar 12. Ends 11 each have a tapered opening 13 formed therein through which a bolt 14 extends vertically with a loose fit. A coil spring 15 encircles each bolt 14 above end 11 and supports a washer 16 upon which the bolt head 25 rests. A nut 17 retains the bolt 14 in operative relation.

A plurality of rigid arms 18 depend from bar 12 in equally spaced relation. The intermediate arms 18 have bifurcated lower end portions 19. 30 Set screws 20 are adjustably threaded in the lower ends of the outer arms 18 and in each fork of the lower portions 19 of the intermediate arms. Centrally between each pair of adjacent arms 18 is journaled a depending arm 21 having a cross head 22 at its lower end substantially horizontally aligned with set screws 20. A pair of rollers 23 is journaled at each end of each cross head 22 by means of a rivet 24 or the like parallel to arm 21. The rollers 23 project beyond the outer ends of cross head 22. Circular plates or flanges 25 are fixedly secured to the intermediate arms 18 and to each rotatable arm 21 intermediate the length thereof in horizontal alignment and concentric thereto. Flanges 25 are of a diameter to provide spaces therebetween somewhat greater than the spacing between opposed rollers 23 and set screws 20. A plurality of cross bars are each rigidly connected to the projecting upper end of a rotatable arm 21 above bar 12. The cross bars are grouped in complementary sets at the opposite ends of bar 12. The outer cross bar 26 of each pair is pivoted at 27 intermediate its ends to a link 28, to which all bars of one group are connected. At the end 50 55 of each outer cross bar 26 opposite arm 21 is

journalized a perpendicular roller 29. The intermediate cross bar 30 of each group is connected to its arm 21 intermediate its ends. One end of cross bar 30 is pivotally connected at 31 to link 28. An elongated coil spring 32 interconnects the opposite ends of the intermediate cross bars 30 of the two groups. The inner cross bar 33 of each group is short, and serves merely for pivotal connection at 34 with link 28.

In normal condition, spring 32 urges cross heads 22 on arms 21 into substantial alignment, with links 28 engaging bar 12 to limit spring urged rotation of arms 21. Elongated cam bars 36 are rigidly positioned adjacent guides 2 adjacent the feed and discharge ends of the device in which the carriers are employed for engagement by rollers 29 to equally rotate all arms 21 to releasing position. Also, at the feed end of the device, similar cams may be provided for engagement by the rollers for the purpose of positively rotating arms 21 to operative locking or gripping position.

The carrier is adapted to grip panels of various thickness by virtue of the adjustability afforded by screws 20. These screws, together with the rollers 23, constitute the only elements which contact the panel, and the contact of each with the panel is substantially a point contact, so that the entire surface of the panel gripped therebetween is exposed for coating when carried into a dipping tank. In this connection, note that the spaced relation of arms 18 and 21 from the panel accommodates such point contact at substantially the center of the panel without interfering with the surface coating. Also, in order to prevent lateral tilting of the panels when centrally gripped at such restricted points, the flanges 25 on arms 18 and 21 are employed, with the spacing therebetween slightly greater than the panel thickness so as not to interfere with coating under normal conditions, but preventing tilting of the panels to an angle at which the panels touch.

Where the carriers are employed to carry small panels, one carrier only is required to support the panel. However, in cases where elongated panels, of the type conventionally employed to form siding, are to be carried, two juxtaposed carriers are employed, each gripping the panel adjacent an end thereof. In such cases, especially where the chains travel in a vertically undulating path, the construction illustrated in Fig. 3 is important to permit the carriers to pivot or shift from normal perpendicular relation to the chains in order to maintain the spacing between the points of contact of the two carriers with the panel while the chains travel along curved portions of guides 2. In this way the points at which the panel are gripped remain constant and danger of damage to the panel as would result from relative movement of the panel and the gripping screws 20 which penetrate slightly into the panel, is avoided. In order to accomplish this carrier pivot, the spring 32 must be stronger than springs 15 at the pivot, since the panel itself serves to transmit the pivoting force.

Another feature of the construction of great practical importance is that, except for the journals of rollers 23, all journals and all control elements are spaced above the panels so that their ready operation is not interfered with by coating thereof by the material into which the panels are dipped.

I claim:

1. The combination with a conveyor, of a car-

rier on said conveyor extending transversely thereof comprising a head, a fixed member depending from said head and normally substantially perpendicular to said conveyor and to said head, a depending member juxtaposed to and spaced from said fixed member and journalized in said head about an axis substantially parallel to said fixed member, a laterally projecting gripping element at the lower end of said journalized member, and a spring normally positioning said journalized member with said gripping element extending therefrom in the direction of said fixed member in article-clamping relation to said fixed member.

2. The construction defined in claim 1, and a roller journalized on the end of said laterally projecting element.

3. The construction defined in claim 1, and a contact member connected with and extending laterally from said journalized member and spaced from said head for operating said journalized member.

4. The construction defined in claim 1, wherein said conveyor includes a flat element supporting and loosely connected with a flat portion of said head by means including a spring normally pressing said head into face engagement with said flat element.

5. The combination with a pair of spaced conveyors each having a projecting part, of an elongated head carried by and extending between said parts, an elongated securing member loosely interconnecting said head and part and projecting thereabove, a coil spring encircling and retained by said securing member and bearing on said head, and a plurality of clamping elements depending from said head.

6. The combination with a conveyor, an elongated transverse head carried by said conveyor, a plurality of fixed fingers depending from said head in spaced relation, a depending finger journalized in said head between each pair of adjacent fixed fingers, clamping elements carried by the lower ends of said fingers, means interconnecting groups of journalized fingers at opposite ends of said head and engageable with said head to limit rotation of said fingers in one direction, and a spring interconnecting said last named means to normally urge the same into engagement with said head.

7. The construction defined in claim 6, and a contact carried by one of said connecting means in projecting relation thereto and adjacent one of said conveyors.

8. The combination with a conveyor, of an article carrier mounted on said conveyor and comprising a head and a pair of juxtaposed spaced clamping members carried by said head and extending at an angle to said conveyor and to said head, one of said members being fixed and the other being rotatable on an axis substantially parallel to said fixed member, at least said rotatable member having a lateral projection, and means normally urging said rotatable member to clamping position with said lateral projection extending in the direction of said fixed member.

9. The combination defined in claim 8, and an elongated member adjacent said conveyor and engageable by said rotatable member for rotating the same.

10. The combination with a conveyor, of a panel carrier mounted on said conveyor and comprising a head, a pair of spaced parallel clamping members depending from said head, one of said members being fixedly secured to said head

and having a laterally projecting part at its lower end, the other member being journaled in said head on an axis parallel to said fixed member and having a laterally projecting part adjacent the projecting part of said first member, and means normally urging said rotatable member to position with its projecting part substantially aligned with the projecting part of said fixed member for gripping a panel between said parts.

10

11. The construction defined in claim 10, and a roller journaled on the free end of the projecting part of one of said members.

12. The construction defined in claim 10, and a collar fixed on each member intermediate its length for engagement by said panel upon tilting thereof.

RALPH N. GEFFROY.
